UNITED STATES PATENT OFFICE

BERT E. MILLS, OF OAK PARK, ILLINOIS, ASSIGNOR TO MILLS NOVELTY COMPANY,
OF CHICAGO, ILLINOIS, A CORPORATION OF ILLINOIS

BOW-CONTROL DEVICE FOR AUTOMATIC CELLOS OR THE LIKE

Application filed June 4, 1928. Serial No. 282,735.

This invention relates to electrically operated musical instruments of the viol class and has for its object the provision in such an instrument of devices for controlling the expression by varying the pressure of the bows on the strings during the operation of the instrument.

A further object of the invention is the provision of expression-controlling devices which vary the rate of speed of the bow motors, as well as the bow pressure on the strings.

Other objects and advantages of the invention will be apparent as it is better understood from the following description, which, taken in connection with the accompanying drawings, discloses a preferred embodiment thereof.

Referring to the drawings,

Figure 1 is a broken elevational view of a bow magnet and bow in normal relation to a string of the instrument;

Fig. 2 is a plan view of the pedals and associated devices for controlling the expression of the instrument;

Fig. 3 is an elevational view of the loud pedal and associated contacts; and

Fig. 4 is a wiring diagram for a hand-played instrument.

Attention is called first to the wiring diagram shown in Fig. 4, which, as above stated, is for a hand-played instrument although it is contemplated that the instrument may be wired for automatic playing, in which case the contacts would, of course, be made through a perforated sheet, in the well known manner, the embodiment of the invention shown in the drawings being illustrative only.

In said Fig. 4, I have shown diagrammatically a series of finger magnets 6, adapted to control the fingering devices of the instrument (which may be substantially as shown in my prior Patent No. 1,425,533, granted August 15, 1922, or of any other known or preferred form), four bow magnets 7 being also shown in this figure and one thereof being shown in Fig. 1. These magnets, in a hand-played instrument, are adapted to be energized by contacts made by actuation of the keys of a keyboard 8, two contacts being made by each key, as indicated by the reference characters

9 and 10 in Fig. 4, one of said contacts being in circuit with the finger magnets and the other with the bow magnets, as will be readily apparent. A bow motor 11, with field 12, and governor 13, is shown at the upper right-hand corner of the diagram and is also shown in Fig. 1. The motor is adapted to be operated continuously during the playing of the instrument, being in circuit, the positive line 14 of which is through the contacts associated with the keys of the keyboard 8 and it being understood that there is a suitable switch (not shown) adapted to control this circuit.

The circuit includes resistance elements, shown at 15 and 16, and associated with said elements is a series of contacts 17-18, 19-20, 21-22, and 23-24. A foot pedal 25 is provided with corresponding contacts 26-27 (see Fig. 2) and when said pedal is depressed, said contacts 26, 27 are adapted to successively engage the pairs of contacts associated with the resistance elements. A wire 28 leads from the resistance to the bow magnets 7 and a wire 29 leads from said resistance to the bow motor 11, a pedal 25 being connected with the negative side of the line, indicated at 30.

A soft pedal 31 is also provided and, as shown, has two positions, one normal and the other neutral. This pedal also connects with the negative side of the line. In normal position, it engages a contact 32, from which a lead 33 takes into the resistance 15, part of which is eliminated when the circuit is through the pedal contact, as it is when said pedal is in normal position. When the pedal is depressed, its contact engages a dead contact 34 and the additional resistance is included in the circuit, said resistance being connected to the negative side of the line at 35. Depression of said pedal thus softens the tone by bringing additional resistance into the operating circuit.

Depression of the pedal 25, however, increases the tone volume by eliminating resistance from said circuit, the amount of resistance eliminated depending on the extent of depression of the pedal.

Referring now to the illustrations of the mechanical devices, it will be observed that the bow magnet 7, shown in Fig. 1, is mounted

above a shaft 36, carrying a bow 37 adapted to play a string 38 of a violin or cello. The bow shaft is normally held raised by means of a spring 39, connected at one end to a hook 40 on said shaft and at the other end to an arm 41, carried by a bracket 42, which supports the solenoid magnet 7. The core member 43 of the solenoid is adapted to depress the bow shaft 36 when the magnet is energized, said shaft having a sleeve 44 thereon which is engaged by said core member 43, a guide bracket 45 being provided on the main bracket 42 to guide said shaft as the same is raised or lowered.

15 The bow shaft is adapted to be rotated by means of the motor 11, to the armature shaft 46 of which said bow shaft is geared, as shown at 47.

As shown in Figs. 2 and 3, the pedal 25 is pivoted at 48 to upstanding ears 49 on a bracket 50 secured to the base 51 of a frame 52. The rear end of the pedal lever, identified by the reference character 53, has a lug 54 thereon, which is connected by a spring 55 with the base, thus holding said lever normally in horizontal position. A stop screw 56, carried by said lever, limits the up movement of the pedal, and a stop screw 57, carried by the lever forwardly of the pivot 48, limits the down movement thereof.

30 The soft pedal 31 is similarly mounted and need not be separately described, except with reference to the control 58 thereon, which, as previously mentioned, normally engages the contact 32 and is movable into engagement with the dead contact 34 when the pedal is depressed.

The contacts 26 and 27 on the pedal 25, and the contact 58 on the pedal 31 are yieldingly mounted, being backed by springs 59 within sleeves 60, having caps 61 on the outer ends thereof, and each of said contacts is connected with the negative side of the line by wires indicated respectively by the reference characters 62, 63, and 64.

As previously indicated, the device is operated merely by depressing the pedals during the playing of the instrument. Depression of the soft pedal increases the amount of resistance in the circuit, thus softening the tone, as has been explained. Depression of the loud pedal 25, however, eliminates resistance from the circuit, causing the bow magnets 7 to exert greater pressure on the bow shafts, thus increasing the tone volume. Such action also increases the speed of the motor 11, and thus the speed of rotation of the bows.

It is thought that the invention and many of its attendant advantages will be understood from the foregoing description, and it will be apparent that various changes may be made in the form, construction, and arrangement of the parts, without departing from the spirit and scope of the invention, or sacrificing all of its material advantages,

the construction hereinbefore described being merely a preferred embodiment thereof.

I claim:

1. In a stringed instrument of the violin class, the combination of fingering devices, bows, bow magnets, an electric circuit including said magnets and resistance elements, and means operable during the playing of the instrument for varying the amount of resistance in the circuit to control the action of the magnets and thus the pressure of the bows on the strings. 70

2. In a stringed instrument of the violin class, the combination of fingering devices, rotatable bows, a motor for rotating the same, bow magnets for raising and lowering said bows with respect to the strings, an electric circuit including said motor, said magnets and resistance elements, and means operable during the playing of the instrument for varying the amount of resistance in the circuit to control the speed of the motor and the force of the magnets, thereby regulating the speed of rotation of the bows and their pressure on the strings. 80

3. In a stringed instrument of the violin class, the combination of fingering devices, bows, bow magnets, an electric circuit including said magnets and resistance elements, and means operable during the playing of the instrument for varying the amount of resistance in the circuit to control the action of the magnets and thus the pressure of the bows on the strings, said means comprising a foot pedal, a series of contacts associated with said resistance elements and a switch element associated with said pedal and adapted to engage said contacts successively as the pedal is depressed to eliminate resistance from the circuit and thereby increase the tone volume. 90

4. In a stringed instrument of the violin class, the combination of fingering devices, bows, bow magnets, an electric circuit including said magnets and resistance elements, and means operable during the playing of the instrument for varying the amount of resistance in the circuit to control the action of the magnets and thus the pressure of the bows on the strings, said means including a soft pedal and contacts associated therewith and with said resistance and adapted upon depression of the pedal to include additional resistance in the circuit to thereby decrease the tone volume. 105

5. In a stringed instrument of the violin class, the combination of fingering devices, bows, bow magnets, an electric circuit including said magnets and resistance elements, and means operable during the playing of the instrument for varying the amount of resistance in the circuit to control the action of the magnets and thus the pressure of the bows on the strings, said means comprising a foot pedal, a series of 115

contacts associated with said resistance elements and a switch element associated with said pedal and adapted to engage said contacts successively as the pedal is depressed 5 to eliminate resistance from the circuit and thereby increase the tone volume, said means also including a soft pedal and contacts associated therewith and with said resistance and adapted upon depression of the 10 pedal to include additional resistance in the circuit to thereby decrease the tone volume.

6. In a stringed instrument of the violin class, the combination of fingering devices, bows, bow magnets, an electric circuit including said magnets and resistance elements, and means operable during the playing of the instrument for varying the amount of resistance in the circuit to control the action of the magnets and thus the 20 pressure of the bows on the strings, said means comprising a foot pedal, a series of contacts associated with said resistance elements and a switch element associated with said pedal and adapted to engage said contacts successively as the pedal is depressed to eliminate resistance from the circuit and thereby increase the tone volume, said means also including a soft pedal and contacts associated therewith and with said resistance 30 and adapted upon depression of the pedal to include additional resistance in the circuit to thereby decrease the tone volume, said soft pedal having two positions and the loud pedal having a greater number of positions, the expression of the instrument being controllable over a range of tone variations corresponding to the combined number of positions of said pedals.

7. In a stringed instrument of the violin class, the combination of fingering devices, rotatable bows, a motor for rotating the same, bow magnets for raising and lowering said bows with respect to the strings, an electric circuit including said motor, said 45 magnets and resistance elements, and means operable during the playing of the instrument for varying the amount of resistance in the circuit to control the speed of the motor and the force of the magnets, thereby regulating the speed of rotation of the bows and their pressure on the strings, said means comprising a foot pedal, a series of contacts associated with said resistance elements and a switch element associated with said pedal and adapted to engage said contacts successively as the pedal is depressed to eliminate 55 resistance from the circuit and thereby increase the tone volume.

8. In a stringed instrument of the violin class, the combination of fingering devices, rotatable bows, a motor for rotating the same, bow magnets for raising and lowering said bows with respect to the strings, an electric circuit including said motor, said 65 magnets and resistance elements, and means

operable during the playing of the instrument for varying the amount of resistance in the circuit to control the speed of the motor and the force of the magnets, thereby regulating the speed of rotation of the bows and their pressure on the strings, said means including a soft pedal and contacts associated therewith and with said resistance and adapted upon depression of the pedal to include additional resistance in the circuit to thereby decrease the tone volume. 70

9. In a stringed instrument of the violin class, the combination of fingering devices, rotatable bows, a motor for rotating the same, bow magnets for raising and lowering said bows with respect to the strings, an electric circuit including said motor, said magnets and resistance elements, and means operable during the playing of the instrument for varying the amount of resistance in the circuit to control the speed of the motor and the force of the magnets, thereby regulating the speed of rotation of the bows and their pressure on the strings, said means comprising a foot pedal, a series of contacts associated with said resistance elements and a switch element associated with said pedal and adapted to engage said contacts successively as the pedal is depressed to eliminate resistance from the circuit and thereby increase the tone volume, said means also including a soft pedal and contacts associated therewith and with said resistance and adapted upon depression of the pedal to include additional resistance in the circuit to thereby decrease the tone volume. 80

10. In a stringed instrument of the violin class, the combination of fingering devices, bows, bow magnets, an electric circuit including said magnets and resistance elements, and means operable during the playing of the instrument for varying the amount of resistance in the circuit to control the action of the magnets and thus the pressure of the bows on the strings, said means comprising a series of contacts associated with said resistance elements and means for making said contacts as desired to control the expression of the instrument. 105

11. In a stringed instrument of the violin class, the combination of fingering devices, bows, bow magnets, an electric circuit including said magnets and resistance elements, and means including a pressure-actuated member operable at will during the playing of the instrument for varying the amount of resistance in the circuit to control the action of the magnets and thus the pressure of the bows on the strings. 110

In witness whereof, I hereunto subscribe my name to this specification.

BERT E. MILLS.
